S. W. BRACK

SINK FOR KITCHEN CABINETS

Filed April 29, 1922

Tr. 50. 1.

Inventor

Susannah W. Brack.

Lacy & Lacy, Attorneys

UNITED STATES PATENT OFFICE.

SUSANNAH W. BRACK, OF WICHITA FALLS, TEXAS.

SINK FOR KITCHEN CABINETS.

Application filed April 29, 1922. Serial No. 557,436.

To all whom it may concern:

Be it known that I, SUSANNAH W. BRACK, citizen of the United States, residing at Wichita Falls, in the county of Wichita and State of Texas, have invented certain new and useful Improvements in Sinks for Kitchen Cabinets, of which the following is a specification.

The present invention relates to a sink for kitchen cabinets, the sink forming a fundamental part of the kitchen and being certainly of more importance than any other kitchen accessory, excepting possibly the cook stove. The sink forming the subject matter of the present invention has the full breadth of the cabinet into which it is built and is considerably longer than an ordinary sink.

Reference is to be had to the accompanying drawing forming a part of the specification and illustrating one embodiment of the invention, corresponding parts in all the figures being indicated by the same reference numerals.

Figure 1 is a longitudinal sectional view of the cabinet with the sink in position; and Figure 2 is a fragmentary perspective view of the sink.

The sink 10 is made practically like other sinks, that is to say, wider at the top than at the bottom but of sufficient breadth to admit of shelves 11 and 12 above it without inconvenience to the front. It rests upon ledges 14 and 15 underneath and is loosely housed by the surrounding walls 16, 17, 18 and 19 of the cabinet and it has a fall towards the right, see Figure 2, which acts as a partial drain to the bottom 9 of the sink.

It has partitioned off corners 20 within it at its lower or right-hand end, as seen in Figure 2 of the drawing, effected by ridges 21 pressed into the metal and these ridges, about one inch in height, bend around the outlet 22, thereby permitting all the water 45 to go direct into the outlet, leaving a dry table bed as it were, that may be termed the primary sink or table. The corners 20 are valuable for soap, parings and the like.

The outlet 22 may be made to empty into 50 an ordinary drain pipe 28 or into a pail or the like.

The front side 23 of the sink 10 is flanged, as at 24, to cover the top edge of the wooden

front wall 19. The back 25 is considerably higher and is preferably in one piece with the sink 10. The two ends 26 and 27 of the sink have their top edges flush with the end walls 16 and 18 respectively, providing uniform depth, as seen in the drawing.

The slanting front 19 admits of the right arm of the user to be rested thereupon, when desired, and permits the use of an adjustable stool 29 during a prolonged task; the open space 30 below the sink admits of the limbs 65 extending the whole way under.

The sink has iron rods or braces 33 passing through its sides 26 and 27 into the wooden wall 16 and middle partition 38 and being secured thereto, as at 35, 36. Thus 70 they hold the two portions firmly together.

The wire shelf 37 forming a secondary top or table is supported by the rods or braces 33 and it not only acts as a drain and table but allows more space for sundry articles that may be slipped under it out of the way. 75 Dishes when washed are stood around and piled upon and underneath it and the whole quantity of crockery can be flushed with boiling water and its heat does most of the drying. Thus is effected three or four washings by handling each piece only one time.

To the left of the sink 10 there is a table top 40. Its inner side edge covers the left end side 27 of the sink 10. Underneath this top 40 is a chest of drawers forming the support for one end of the sink 10.

The lower shelf 11 and the two upper shelves 12 and 39 may be slightly slatted. The safe 41 opens downwardly, sustained 90 by chains 42.

Leaves 43 and 44 are hinged as at 46 and 47 at the ends of the cabinet and the right hand leaf 43 rests over the edge of the sink 10 shielding the wooden edge of the wall 16 and the side 26 of the sink.

Having thus described the invention, what is claimed as new is:

1. In a sink construction, a sink of uniform depth and a housing therefor; means in said housing supporting the sink with its bottom inclined, a V-shaped ridge on the bottom of the sink extending between the front and rear sides thereof, the apex of the ridge being situated adjacent the lower end of the bottom and a drain hole being 100 provided within the apex of said ridge. 105

2. In a sink construction, a sink and a housing therefor, and a V-shaped ridge on the bottom of the sink extending from the front and rear sides thereof, the bottom of the sink extending from the front and rear sides thereof, the apex of the ridge being situated adjacent the lower end of the bottom.
3. In a sink construction, a sink and a housing therefor supporting the sink with bottom inclined, and a V-shaped ridge on the bottom of the sink extending from the front and rear sides thereof, the apex of the ridge being situated adjacent the lower end of the bottom.

In testimony whereof I affix my signature,

SUSANNAH W. BRACK. [L.S.]
